UNITED STATES PATENT OFFICE.

THOMAS A. BRAGG, OF TOLEDO, OHIO, ASSIGNOR TO THE OWENS BOTTLE COMPANY, OF TOLEDO, OHIO, A CORPORATION OF OHIO.

MOLD-FINISHING MACHINE.

Application filed December 24, 1919. Serial No. 347,244.

To all whom it may concern:

Be it known that I, THOMAS A. BRAGG, a citizen of the United States, residing at Toledo, in the county of Lucas and State of Ohio, have invented new and useful Improvements in Mold-Finishing Machines, of which the following is a specification.

My invention relates to improvements in machines for cutting or engraving molds or dies or for re-producing in cameo or intaglio and is herein shown applied to a machine of the general type disclosed in the patent to Keller and Warman, 956,769.

An object of the invention is to provide a novel form of clamping device by which the pattern and the molds or dies may be quickly and securely clamped in position on the machine. Another feature relates to the means for supporting the molds in position on the work tables. A further feature of the invention consists in the provision of suitable means for oscillating the work table about a vertical axis so that when cutting or engraving a curved surface, as for example, the inner concave surface of a mold, said surface may be maintained approximately perpendicular to the cutting tool.

Other features of the invention will appear hereinafter.

30 In the accompanying drawings:

Figure 1 is an elevation of a machine to which my invention is applied.

Figure 2 is a sectional plan showing particularly the mounting of the work frame for oscillating movement about a vertical axis.

Figure 3 is a plan of the machine.

Figure 4 is a detail showing means permitting a horizontal adjustment of the work supporting frame.

Figure 5 is a fragmentary elevation showing a mold or die and the means by which it is clamped in position on the work table.

Figure 6 is a detail showing the pivotal mounting of a lever through which motion is transmitted to the swinging work carrying frame.

Figure 7 shows a bearing plate for a work holding clamp.

50 Figure 8 is a view of the clamp.

Figure 9 is a view of a plate for positioning a mold on the work table.

Figure 10 is a view similar to Figure 5,

showing a templet clamped on the work carrying frame.

Figure 11 is a section of the same, showing the arrangement for adjustably clamping the templet in its holder.

Figure 12 is a perspective view of the templet.

Figure 13 is a detail showing a cutter and a work piece arranged at an angle thereto.

Figure 14 is a view similar to Figure 3, but with the parts in a different position.

The machine comprises a stationary 65 frame A including a standard 15 and a horizontally disposed portion 16 (Fig. 14). A work carrying frame B comprises a vertical back plate 17, work holding tables 18 projecting forwardly therefrom and vertical 70 parallel bars 19 attached to the front ends of the work tables. The work frame B is adjustably mounted on a vertically disposed supporting frame D. One or more guide bars 20 (Fig. 1) attached to the rear face 75 of the plate 17 and extending transversely thereof, fit in correspondingly shaped grooves in the frame D, thereby permitting lateral adjustment of the work frame B for adjusting the work thereon to the cutter. 80 The work frame is held in adjusted position by means of a locking pin 22 extended through an opening in the plate 17 and into one of a series of openings 23 in the plate D. Said locking pin is carried by a hand operated lever 24 mounted on the work frame. 85

The frames B and D are moved up and down by means of a vertical driving shaft 25 having a screw threaded connection with rearwardly projecting arms 26 (Fig. 2) on the frame D. The shaft 25 may be driven by an electric motor connected thereto through speed changing gearing and a reversing clutch contained within a casing 27. Said clutch and gearing may be of standard construction such as shown, for example, in U. S. Patent 1,358,929, granted to me on November 16, 1920. The reversing clutch is actuated by a lever 28 to which is attached a vertical rod 29 having thereon adjustable 95 lugs 30 and 31. As the work frame moves upward a tappet 32 thereon engages the lug 30 and raises the rod 29, thereby shifting the clutch and reversing the direction of rotation of the shaft 25. The work frame then 100 travels downward until the tappet engages

the lug 31 and again shifts the clutch and reverses the direction of feed.

Work pieces 33, here shown as hollow mold sections, are mounted on upper and lower mold tables 18. A pattern or templet 34 having a concave surface 35, to the shape of which the mold cavities are to be cut, is mounted on an intermediate table 18. The templet is adjustably mounted in a supporting block 36. Adjusting screws 37 permit a nice adjustment of the templet in a forward or rearward direction. It is also adjustable up and down and locked in adjusted position by set screws 38. Plates 40 are removably mounted on the tables 18, said plates being cut away to form semi-circular or other shaped recesses to receive the work pieces and hold them in position. These plates are interchangeable and may be made of various forms corresponding to different shaped work pieces.

A clamping device is provided for each die and templet, said device comprising a bar or bracket 41 having a central threaded opening in which is an adjustable screw rod 42, the outer end of which is adapted to bear against the templet or die. The latter may be provided with a lug 43 or other bearing surface for the end of the rod 42. Studs 44 and 45 are adjustably mounted in the ends of the bar 41 and have their outer ends rounded to form ball bearing surfaces. When the clamp is in position these lugs engage in recesses 46 formed in a plate 47 attached to the plate 17. The stud 45 has a threaded connection with the bar 41 and is adjusted therein before the clamp is placed in position. After the clamp is placed on the machine it is tightened up by means of a hand screw 48 connected to the stud 44 for forcing the latter rearwardly. It will be seen that with this construction all that is necessary to clamp the work piece in position is to place the clamp behind the work piece and tighten it up by turning the handle 48. The clamp is arranged with the rod 42 in a downwardly and forwardly inclined position so that the work piece is held firmly in its forward position and also held solidly down on the table 18.

Rotary cutters 50 for operating on the work are carried on a frame 51 mounted to swing about a vertical axis 52 for moving the cutters toward and from the work. These cutters and the tracing tool are rotated as usual by a motor 53 having suitable driving connections with the spindles on which said cutters and tool are mounted. The swinging frame 51 is carried on a frame 54 mounted for transverse sliding movement on the frame A for feeding the cutters across the work pieces. This movement of the frame 54 is effected by any suitable mechanism, as for example, that shown in

the patent to Keller above referred to. A 65 rack 55 and pinion 56 permit hand adjustment of the frame 54. The path of the cutters as the work frame moves up and down, is controlled as usual by a stylus traveling in contact with the pattern 35. 70

The templet 34 is preferably made of hardened cast iron instead of the usual bronze or steel templet. The block of iron for forming the templet or model is first cast, then surface finished, then hardened 75 and where necessary further finished to correct any defects due to warping while being hardened. The use of hardened cast iron is of value because it resists the wear of the tracing tool. Ordinary cast iron will not 80 stand the wear of the continuously rotating tool which bears with considerable pressure against it. The use of bronze which has heretofore been commonly employed is objectionable on account of the difficulty and 85 expense of shaping and finishing it. A similar difficulty arises in the use of steel. The cast iron models can be made with comparative ease and are found to be highly satisfactory, owing to their great resistance to 90 wear.

In order that the cutters may at all times be substantially perpendicular to the cutting surface along which they are working, I provide automatic means for swinging the 95 work table about a vertical axis in synchronism with the movements of the frame 54. For this purpose the frames B and D (Fig. 2) are connected to swing with a frame E horizontally about the shaft 25 as an axis. 100 The frame E is provided with a rearwardly extending arm 57 connected through a link 58 with a lever 59. Said lever is mounted to swing about a fulcrum pin 60 mounted in an arm 61 on the frame A. The lever 105 is adjustable by means of a longitudinal slot 62 therein through which the fulcrum pin extends, the lever being held in its adjusted position by a set screw 63 (Fig. 6) which clamps the lever in a pivot block 64 journaled on the pin 60. The lever 59 is connected through a link 65 to the frame 54. When the frame 54 is moved to the left, as shown in Figure 14, the work frame B is 110 swung to the left as shown, whereby the 115 surface on which the cutter 50 is operating is kept substantially perpendicular to the cutter (see Fig. 13). In like manner as the frame 54 travels to the right the work frame also swings to the right and its angular position changes so that the work surface remains about perpendicular to the cutter at the point at which the cutter is operating. The extent of this angular movement of the work may be adjusted by adjusting the 120 lever 59 to vary its fulcrum point. This adjustment is such that the horizontal movement of the work piece is less than that of 125

the cutters so that the movement of the frame 54 will feed the cutting tools across the work surfaces.

Modifications may be resorted to within 5 the spirit and scope of my invention.

What I claim is:

1. The combination of a work frame comprising horizontally disposed work holding tables arranged one above another and vertically disposed front and rear frame members, said tables forming supports for work pieces carried thereon in position to bear against said front frame member, and clamps interposed between the work pieces 15 and the said rear frame member while the work pieces are in said position, said clamps arranged to apply a forward and downward pressure to the work pieces.

2. The combination of a work frame comprising horizontally disposed work holding tables and vertically disposed front and rear frame members, said tables forming supports for work pieces carried thereon in position to bear against said front frame member, 25 clamps interposed between the work pieces and the rear frame member while the work pieces are in said position, said clamps each comprising a transverse bar, studs projecting rearwardly from said bar to bear against the rear frame member, and an intermediate 30 clamping rod projecting forwardly and downwardly from said bar to bear against the rear face of a work piece.

3. The combination of a work frame comprising horizontally disposed work holding tables and vertically disposed front and rear frame members, said tables forming supports for work pieces carried thereon in position to bear against said front frame member, 40 clamps interposed between the work pieces and the rear frame member while the work pieces are in said position, said clamps each comprising a transverse bar, studs projecting rearwardly from said bar, and bearing plates 45 interposed between said rear frame member and said studs, the bearing plates being formed with concave bearing surfaces for said studs, one of said studs having a screw threaded connection with the clamp bar.

50 4. The combination with a frame to hold a templet or work piece having a concave surface, a tool holding frame, a tool carried thereby arranged to bear against said concave surface, means to move said tool holding frame and tool transversely of said surface, and mechanical connections between said frames through which movement is transmitted from the tool holding frame to the work holding frame and an angular 55 movement thereby imparted to the work holding frame as the tool is moved transversely of said surface to thereby change the angle of the frame to the tool.

5. The combination of a work holding 60 frame to support a work piece having a con-

cave surface, a cutting tool, a frame carrying said tool and arranged to hold the latter against said surface substantially perpendicular thereto, means to move the tool carrying frame and thereby feed said tool across said surface, and mechanical connections between said frames through which the movement of the tool carrying frame is transmitted to the work frame and operates to so change the angular position of the 70 work frame that the cutter is kept substantially perpendicular to the surface at the point of contact therewith.

6. The combination of a work frame arranged to support a work piece having a concave surface, of a tool holding frame, a tool carried thereby and arranged to bear against said surface with the tool substantially perpendicular to said surface at its point of contact, means to feed said tool holding 80 frame transversely to the work frame, and connections between said frames through which the tool holding frame operates to swing the work frame as the tool advances and thereby change the angular position of 85 said concave surface so that the tool remains approximately perpendicular to the surface at the point of contact therewith.

7. The combination of a work holding frame, a tool holding frame, a carriage on which the tool holding frame is mounted, said carriage mounted to travel horizontally, 90 said work holding frame mounted for oscillating movement about a vertical axis, and link and lever connections between the work holding frame and said carriage for oscillating the work holding frame as the carriage reciprocates.

8. The combination of a work holding frame, a tool holding frame, a carriage on 105 which the tool holding frame is mounted, said carriage mounted to travel horizontally, said tool holding frame mounted for oscillating movement about a vertical axis, a lever, links connecting opposite ends of said 110 lever to the carriage and work frame respectively for oscillating said work frame when the carriage reciprocates, and means for adjusting the fulcrum point of said lever to thereby vary the relative movement of the 115 carriage and said frame.

9. The combination of a work holding frame, a tool holding frame, a carriage on which the tool holding frame is mounted, said carriage mounted to travel horizontally, 120 said tool holding frame mounted for oscillating movement about a vertical axis, a lever, and links connecting opposite ends of said 125 lever to the carriage and work frame respectively for oscillating said work frame when the carriage reciprocates.

Signed at Toledo, in the county of Lucas and State of Ohio, this 5 day of December, 1919.

THOMAS A. BRAGG.
